UNITED STATES PATENT OFFICE.

LEWIS SMITH HENDRICKS, OF MOUNDSVILLE, WEST VIRGINIA.

KEYLESS LOCK.

1,261,932.

Specification of Letters Patent.

Patented Apr. 9, 1918.

Application filed December 6, 1917. Serial No. 205,849.

To all whom it may concern:

Be it known that I, LEWIS SMITH HENDRICKS, a citizen of the United States, and a resident of Moundsville, in the county of Marshall and State of West Virginia, have invented a certain new and useful Improvement in Keyless Locks, of which the following is a specification.

The present invention relates to locks, and 10 more particularly to certain improvements in that type known as padlocks.

An object of the present invention is to provide a lock which may be manipulated without the use of a key; a lock which cannot be picked or opened by an unauthorized person; a lock which is substantial and capable of withstanding considerable strain; a lock which embodies the structure requiring not only the operation of certain of its parts 20 in predetermined directions and sequence, but which also requires the certain positioning or turning over of the body of the lock for effecting the operation of certain gravity actuated elements of the lock structure.

25 The invention also aims at the provision of a lock of this type which embodies the above enumerated characteristics, and which at the same time is of relatively simple and economical construction.

30 The above and various other objects and advantages of this invention will be in part described, and in part understood, from the following detailed description of the present preferred embodiment, the same being 35 illustrated in the accompanying drawing, wherein:

Figure 1 is a front elevation of a lock constructed according to the present invention.

40 Fig. 2 is a longitudinal section taken in an edgewise direction through the lock, showing the shackle thereof in locked position.

Fig. 3 is a longitudinal transverse section taken through the lock centrally thereof.

45 Fig. 4 is a view similar to Fig. 2, inverted, and disclosing certain additional parts of the lock mechanism in section, and showing the elements of the lock in released positions.

50 Referring to the drawing 10 designates the casing of a lock which, in the present instance, is of elongated substantially rectangular construction and adapted to be closed at its open side by a plate 11. The casing 10 is provided with an opening in one end, which end is designed to constitute the up-

per end of the lock. Arranged longitudinally within the casing 10 is a wall or flange 12 located at one side of the opening in the casing and extending throughout the length 60 of the casing. A web 13 of substantially L form is arranged in one of the lower corners of the casing and forms a supporting shoulder. The web 13 extends to a point near the longitudinal axis of the casing and forms 65 a chamber into which a key may be inserted through a key-hole slot 14 formed in the cover plate 11. If desired the casing 10 may be provided with guards 15 within the web 13 adapted to engage the wards of a key 70 which may be inserted through the slot 14 in an attempt to maliciously open the lock. The guards 15 may be constructed to prevent the rotation of the ordinary key so as to mislead unauthorized parties tampering 75 with the lock into believing the lock requires a special key.

Slidable within the casing 10 is a shackle 16. The shackle 16 has a long leg 17 extending into the casing 10 against the guide 12 80 and has a short leg 18 projecting but a short distance into the opening of the casing when the shackle is closed. The long leg 17 is provided, near its outer end, with a projection 19 in the form of a guard which extends 85 toward the axis of the short arm 18 and is spaced sufficiently below the same to admit free access to and from the loop of the shackle. The casing 10 and the cover plate 11 are recessed at opposite sides to conform 90 to the loop of the shackle when the latter is closed.

The long leg 17 of the shackle has a longitudinal opening into which slidably engages a guide pin 20, the latter being riveted or otherwise suitably secured in the lower edge of the casing 10 and extending throughout the entire length thereof, and slightly above the casing. The guide rod 20 has a spring 21, of preferably the helical type, surrounding the base portion of the rod and adapted to bear at its free end against the arm 17 to urge the shackle upwardly through the casing.

To lock the shackle against upward movement a gravity latch lever 22 is provided, the same being pivoted upon a transverse pin 23 mounted in the casing and substantially intersecting the longitudinal axis of the casing. The latch lever 22 has an enlarged head or weight on one end adapted to rest upon the shoulder 13 and has a nose 24

extending downward at an angle to seat against a shoulder or projection 25 formed upon the lower end and inner side of the leg 17. The spring 21 urges the leg 17 upward and binds the shoulder 25 against the gravity latch lever, which latter is held from releasing the shackle by the shoulder 13, and also by the inclined nose of the latch.

A locking lever 26 is pivoted on a transverse pin 27 in the upper corner of the casing 10 over the shoulder 13 and opposite to the leg 17. The locking lever 26 extends longitudinally within the casing and has a shouldered end 28 lying beneath the short leg 18 and an opposite reduced arm 29 extending downward in the casing and adapted to swing toward and from the weight or head of the latch lever 22. The head of the lever 22 has an upwardly facing shoulder 30 formed by notching the outer end of the head for the reception of the arm 29 thereagainst to retain the lever 22 from swinging away from the shoulder 13. A leaf spring 31 is fixed to one edge of the casing below the pin 37 and bears at its free end against the arm 29, urging the latter against the head of the latch lever.

The shackle 16 is normally retained from downward movement against the tension of the spring 21 by a locking bolt 32 seated in a groove formed in the outer end of the shackle and extending edgewise through the same. The said slot is preferably undercut or of dove tail form, and the bolt 32 is of corresponding form, the bolt preferably having its upper edge extending beyond the upper edge of the shackle, and having its ends conforming to the edges of the shackle to appear as a part thereof. The bolt 32 has a longitudinal recess 33 in its lower side and through which projects a stop pin 34 secured transversely through the shackle between the edges. The guide rod 20 is of a length to lie flush with the inner face of the dove tail groove when the shackle is moved up by the spring 21 against the nose 24 of the latch. The bolt 32 is adapted to be slid into position with its ends flush with the edges of the shackle, in which position the bolt 32 engages over the free end of the rod 20 and holds the shackle from downward movement over the rod.

In operation, when the parts are locked, as shown in Figs. 2 and 3, the shackle 16 cannot be moved inward as the bolt 32 bears against the guide rod, and cannot be drawn outward as the nose 24 of the gravity latch lever bears against the shoulder 25 of the shackle and the head of the latch lever rests against the shoulder 13. The arrangement is such that the shoulder 13 is not essential to retain the latch lever from releasing the shackle, for the nose 24 extends obliquely downward and not only against the shoulder 25 but also against the inner edge of the

leg 17. Therefore, any attempt to withdraw the shackle is resisted by the nose 24 as it binds against its pivot 23 and prevents upward movement of the leg 17.

To release the shackle it is necessary first 70 to slide the bolt 32 into the position shown in Fig. 4 for releasing the guide rod 20. The shackle 16 may be now forced inward against the tension of the spring 21. The short arm 18 engages the end 28 of the locking lever and retracts its arm 29 from the gravity latch lever 22 against the tension of the spring 31. The shackle is held in such retracted position while the casing 10 is inverted, as shown in Fig. 4 whereupon the 80 weighted latch lever 22 swings about its pivot 23 out of the path of shoulder 25 and releases the nose 24 from the shackle. The inward movement of the shackle carries the shoulder 25 away from the nose 24 to an 85 extent sufficient to free the nose and admit the swinging of the latch lever by gravity. The movement of the latch lever turns the shoulder 30 thereof out of the path of arm 29, so that the shackle may now be drawn 90 outward and the arm 29 may bear idly against the curved peripheral surface of the weighted head.

To lock the shackle again, it is only necessary to turn the casing 10 into upright position and to force the shackle 16 down over the guide rod 20 and against the spring 21. Such operation brings the shouldered projection 25 against the nose 24 of the gravity lever and forces the same about its pivot to 100 an extent sufficient to permit the nose to rise above the shoulder 25. The shackle is now released and the spring 21 raises the same into contact with the gravity latch lever and at the same time releases the locking lever 26. The locking lever 26 is urged by its spring 21 into interlocking engagement with the latch lever. The bolt 32 is now slid into closed position over the end of the rod 20 and prevents the release of the parts.

It is of course understood that various changes and modifications may be made in the details of construction and design of the above specifically described parts of this invention without departing from the spirit 115 thereof, the changes and modifications being restricted only by the scope of the following claims.

What is claimed is:

1. In a lock, the combination of a casing, 120 a shackle slidable in the casing, a gravity latch lever pivoted in the casing adapted to engage the shackle to prevent withdrawal of the shackle and being adapted to be released therefrom by a movement of the shackle and the overturning of the casing, and means for normally preventing said movement of the shackle.

2. In a lock, the combination of a casing, 125 a shackle in the casing, a gravity actuated 130

latch lever pivoted in the casing for interlocking engagement with the shackle to prevent release thereof, a locking device for said latch lever normally engaging the same to hold it in the path of the shackle and having a part in the path of the shackle, and a spring engaging the shackle to normally urge it into interlocking engagement with the latch lever and out of contact with the locking device.

3. In a lock, the combination of a casing, a shackle mounted in the casing, a gravity actuated latch lever pivoted in the casing and adapted to engage the shackle to prevent release thereof, and a locking lever pivoted in the casing adapted to engage said latch lever to hold it from disengagement relative to the shackle and having a portion in the path of the shackle adapted for engagement thereby upon a predetermined movement of the shackle for releasing said parts.

4. In a lock, the combination of a casing, a shackle slideable in the casing, a latch lever pivoted in the casing and adapted to engage the shackle to hold the latter from withdrawal from the casing, a locking lever pivoted in the casing for interlocking engagement with the latch lever to hold it against the shackle and having a part in the path of the shackle to be engaged thereby when the shackle is moved inward for releasing the locking lever from the latch lever, and means on the shackle normally holding the latter from inward movement.

5. In a lock, the combination of a casing, a shackle slideable in the casing and having a shoulder, a gravity latch lever in the cas-

ing for engagement with the shoulder to hold the shackle from withdrawal, a locking lever in the casing adapted for interlocking engagement with the latch lever to hold the latter against said shoulder and having a part lying in the path of the shackle to be engaged thereby when the shackle is moved inward to release said shoulder from the latch lever and release the locking lever from the latch lever, whereby said latch lever when the casing is overturned being adapted to swing out of the path of the shoulder, and means for normally retaining the shackle from inward movement.

6. In a lock, the combination with a casing, a shackle slideable in the casing and having a long leg and a short leg, a guide rod secured to the bottom of the casing and slidably projecting through the long leg, a spring surrounding the base of the rod to normally urge the shackle outward, a gravity latch lever pivoted in the casing for interlocking engagement at one end with said long leg and a spring being adapted to yieldingly hold the long leg against said lever, a locking lever pivoted in the casing and having one end for interlocking engagement with the latch lever when engaging said long leg, and having an end lying in the path of said short leg of the shackle to be engaged thereby when the shackle is moved inward against the tension of said spring, and a bolt slidably mounted in the outer end of the shackle adapted to engage the outer end of said guide rod to hold the shackle from inward movement.
